CLAIM

The ornamental design for an animal feeder as shown and described.

DESCRIPTION

FIG. 1 is a front perspective view of an animal feeder showing our new design;

FIG. 2 is a right perspective view of the animal feeder shown in FIG. 1;

FIG. 3 is a bottom perspective view of the animal feeder shown in FIG. 1;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged detail view taken from encircled area 10 in FIG. 1.

The broken lines in the drawings depict portions of the animal feeder that form no part of the claimed design.
